UNITED STATES PATENT OFFICE

104,089

DESIGN FOR A DRESS ENSEMBLE

Jack Bowdan, New York, N. Y.

Application March 12, 1937, Serial No. 68,126

Term of patent 3½ years

To all whom it may concern:

Be it known that I, Jack Bowdan, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The rear portion of the dress unit is conventional.

The elliptical units appearing along the front and shoulder portions of the cape, and on the front bust portion of the dress unit, represent raised air-tucks.

I claim:

The ornamental design for a dress ensemble, substantially as shown, and described.

JACK BOWDAN,
